US0D1097389S

(12) **United States Design Patent** (10) Patent No.: **US D1,097,389 S**
Vazquez Hernandez et al. (45) Date of Patent: ** Oct. 7, 2025

(54) **PRESSURE WASHER**

- (71) Applicant: **Karcher North America, Inc.**, Aurora, CO (US)
- (72) Inventors: **Gerardo Vazquez Hernandez**, San Nicolas de los Garza (MX); **Eddy Diaz Flores**, China (MX); **Carlos Ramirez Gonzalez**, Guadalupe (MX)

- (73) Assignee: **Karcher North America, Inc.**, Aurora, CO (US)

(**) Term: **15 Years**

(21) Appl. No.: **29/916,234**

(22) Filed: **Nov. 9, 2023**

(51) LOC (15) Cl. **15-05**

(52) U.S. Cl.

USPC **D32/15**

(57) **CLAIM**

The ornamental design for a pressure washer as shown and described.

DESCRIPTION

FIG. 1 is a front perspective view of the pressure washer;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

The dotted lines showing portions of the pressure washer depict environment and form no part of the claimed design.
